PIPE

Apollo Torrese, Philadelphia, Pa.

Application October 24, 1933, Serial No. 694,928

1 Claim. (Cl. 131—12)

This invention relates to pipes, and has for an object to provide a pipe having improved means for providing reversely directed flow of smoke within the stem.

5 A further object of the invention is to provide a pipe having a tube inserted into the stem, producing an annular space, and with a mouthpiece having a tube inserted into the first mentioned tube for directing the flow of smoke reversely within the stem.

10 The invention, therefore, comprises a pipe embodying a bowl, a stem and a mouthpiece, the stem being bored to receive a tube therein and the mouthpiece being provided with a conduit insertable into the tube, with means for making relatively smoke and air-tight connection between the tube and the mouthpiece, with the exception of a channel provided for the purpose of admitting smoke from the annular space about the tube into the interior of the tube, and from the interior of the tube into the conduit and therefrom into the mouthpiece.

15 The drawing illustrates an embodiment of the invention and the views therein are as follows:

20 Figure 1 is a view of the pipe in longitudinal section upon a plane substantially axial of the bowl,

25 Figure 2 is a view in elevation of the mouthpiece and its associated parts,

30 Figure 3 is a transverse sectional view taken on line 3—3 of Figure 1,

35 Figure 4 is a transverse sectional view taken on line 4—4 of Figure 1, and

40 Figure 5 is a perspective view of the tube, it being understood that all of Figures 3, 4 and 5 are on a scale greatly enlarged relative to Figures 1 and 2.

Like characters of reference indicate corresponding parts throughout the several views.

45 The pipe as an entirety comprises a bowl 10, a stem 11 and mouthpiece 12. These may be of any usual and ordinary shape, to meet the demand of the trade, and the exact shape as shown in the drawing is only illustrative, and no limitation upon the invention.

50 The stem 11 is bored to receive the tube 13 and to provide an annular space 14 about said tube. One end of the tube is closed, as at 15, and the opposite end is provided with a plug 16 having a shoulder 17, which is of substantially the same diameter as the tube, and both the shoulder 17 and the plug 16 are provided with a continuous groove 18. The plug 16 carries the conduit 19 which extends within the tube 13 and adjacent to the closed end 15 thereof.

55 Beyond the shoulder 17 the plug is continued by a constricted neck portion 19' which is attached to the part 20 of the mouthpiece 12 which is inserted within the bore of the stem. Preferably, the bore of the stem will be cylindrical

throughout its extent, and will communicate by means of a passage 21 with the bowl 10.

60 The arrangement is such that a chamber 22 is provided between the end of the tube 13 and the end of the bore, and a corresponding chamber 23 is provided by the constricted section 19' attached to the mouthpiece.

In use, smoke from the bowl 10 will pass through the vertical passageway 21 into the chamber 22 and from there through the annular space intervening between the tube 13 and the inner wall of the bore of the stem. The smoke will then reach the chamber 23 and will pass from this chamber 23 through the groove 18 into the interior of the tube 13, and the length of 15 the tube 13 and enter the end of the conduit 19, passing through said conduit, through the plug 16 and constricted neck 19' into and through the mouthpiece 12.

65 It is intended that the tube 13 shall fit upon the plug so tightly that when the mouthpiece is removed from the stem by withdrawing the constricted portion 20, the tube 13 will be removed therewith. After this removal the plug 16 and conduit 19 may be removed from the tube 13, 25 whereupon the mouthpiece, with its associated parts, will be as shown at Figure 2, are accessible for cleaning; likewise the tube 13 will also be accessible for cleaning as well as the bore of the stem and the chamber 22.

70 By the construction and arrangement outlined, a pipe is provided with a considerably augmented conduit for cooling the smoke and at the same time the chamber 22 is provided for receiving moisture resultant from the combustion of the 35 tobacco in the bowl 10, and moisture from the mouth of the user will pass through the conduit 19 into the tube 13.

75 The moisture from the two sources, therefore, will not commingle and the whole structure may be readily and conveniently cleaned when fouled.

80 Of course, the pipe herein illustrated may be modified and changed in various ways without departing from the invention herein set forth and hereafter claimed.

85 I claim:—

A pipe comprising a stem, a mouthpiece inserted by a sliding fit into the stem, a cylindrical plug fixed to the mouthpiece, a cylindrical tube carried by the plug, said plug having a shoulder spaced from the stem and the mouthpiece and having a longitudinal groove and a cylindrical closed end imperforate sleeve fitted onto the plug and abutting the shoulder, said sleeve being spaced from the walls of the stem throughout its entire length and the tube within spaced from the sleeve and all removable with the mouthpiece, said sleeve being removable from the tube and plug.

APOLLO TORRESE. 60
